UNITED STATES PATENT OFFICE.

PAUL BARNUM, OF SAN FRANCISCO, CALIFORNIA.

WALL-BED.

1,097,903.

Specification of Letters Patent. Patented May 26, 1914.

Application filed October 14, 1913. Serial No. 795,077.

To all whom it may concern:

Be it known that I, PAUL BARNUM, a citizen of the United States, residing in the city and county of San Francisco and State 5 of California, have invented new and useful Improvements in Wall-Beds, of which the following is a specification.

This invention relates to wall beds, and particularly to a wall bed in combination 10 with a hollow revoluble door.

An object of the present invention is to design a wall bed in which there is provided a hollow revoluble door structure with guide-ways having coöperative relation with 15 a bed structure, said door being so pivoted as to revolve about a vertical axis and be engaged and stopped in either of its positions by the usual door stop or bead on one of the jambs of the doorway.

20 A further object of the invention is to provide a bed structure comprising a frame movable from a vertical position to a horizontal position, or vice versa, said frame being approximately of equal length to the 25 height of the door, and to so connect said frame to the guideways of the door that the frame when adjusted upright will not extend above the height of the door.

A further object of the invention is to 30 provide counterbalancing means connected to a hinge plate which has coöperative engagement with the guide ways, and upon which the head end of the bed is hingedly connected; means being provided for maintaining the traveling hinge plate, or plates, 35 without change of angular relation to the guides or door, said means comprising an automatically operating link having a pivotal relation to the bed frame, so that during 40 the movement of the latter from one position to another said device will control the hinge plates.

A further object of the invention is to 45 provide in combination with a relatively stationary support at the head of the bed, and a bed frame vertically and horizontally adjustable with relation thereto, means for transmitting to said support the weight of 50 the bed frame, and an automatically operating carriage pivoted upon and adjacent the foot of the bed frame so that as the latter moves to horizontal position said carriage will come into operation to support the outer end of the bed; and an important object 55 of my present invention is to provide an article of manufacture comprising a sub-

stantial, frame structure to which may be readily attached and detached door-forming panels, said frame structure being provided with guideways and having pivot bearings 60 for supporting a folding bed frame, said door frame having a vertical pivotal member centrally located between its vertical edges and offset as to the center line of the thickness of the door, so that when the door-forming panels are mounted upon the door frame, the revoluble door structure will be stopped by engagement in either of its positions when turned about the pivot by a single stop bead on a jamb at one side of 65 the doorway.

Other objects and purposes of this invention will be made manifest in the following specification.

The invention consists of the parts and 75 the construction and combination of parts as hereinafter more fully described and claimed, having reference to the accompanying drawings, in which,

Figure 1 is a side elevation of the bed 80 structure in horizontal position, and partly broken away, showing the hollow door in each view. Fig. 2 is a top plan view of the bed structure folded into vertical position, and showing the door structure partly 85 broken away. Fig. 3 is a detail view of the reinforced bed end member. Fig. 4 is a detail view showing the connection between the suspension pin and the hinge plate or traveler. Fig. 5 is a side elevation of the 90 device with the bed frame adjusted in vertical position and showing the hollow door and door frame partly in section. Fig. 6 is a front view of the bed structure, partly broken away to show the door which is 95 partly broken away.

In the illustrated mounting of my bed structure, a portion of a wall 2 is shown in which there is provided a doorway 3, at one side of which is a jamb 4 with the usual 100 stop-bead or stop 5; in the other side of the doorway there being a jamb 6 past which one edge of the door structure 7 will swing freely without counter-engagement, the only stop acting to limit the motion of the 105 door from one side to the other about its pivot 8 being the ordinary jamb stop 5.

One of the features or objects of my invention is a door structure consisting of a central rectangular frame 9, with vertical 110 stiles and transverse end members 10 and 11 at the top and bottom, respectively; there

being readily and removably attachable to one side of the door frame 9 a door panel 12 of substantially equal width to the doorway 3, and to the opposite side of the door frame or skeleton 9 another panel 13 which is of somewhat less width than the main panel 12, both of these panels being respectively attached to the skeleton frame 9 by a suitable fastening device as screws 14. Thus I provide the skeleton or body frame 9, which may be manufactured as a stock article and element of my bed structure and supplied to contractors and builders, who may provide the panels 12 and 13 finished in harmony with the interior finish of the building.

In order to utilize a single stop, as the usual jamb bead 5, at one side of the doorway 3, as a means for limiting and positioning the door structure, I have shown the vertical pivot rod as located to one side laterally of the panel 12 and approximately in the central vertical plane of the stop bead 5, the pivot 8 passing vertically through the hollow door structure and being securely mounted in the body frame 9 thereof, and having bearings 14 at the top of the doorway, and 15 in the floor, and when the door structure is turned from a position in Fig. 2, where the panel 12 is behind the stop 5, into a position in front thereof by movement in the direction of the arrows *a—b*, Fig. 2, the door panel 12 will shift its position to the opposite side or in front of the stop 5, which will be engaged by the front edge of the door panel 12 adjacent a knob latch 16, which is designed to latch with a keeper 17 in the door jamb 6 when in juxtaposition therewith; this latch 16 serving to steady the door while the folding bed structure to be hereinafter described is adjusted. Any suitable type of stock latch may be employed at the location of the latch 16, and a further stock latch 18 may be employed if desired at the jamb 4 for engagement with the adjacent edge of the door panel 12.

Rigidly secured to the skeleton frame 9 of the door are suitable rails 19, extending vertically and forming guideways upon each of which travels a roller 20, which is mounted upon a journal 21, which is rigidly secured to a flat plate forming a traveler or hinge 22, there being one plate 22 for each of the guideways 19, the plate standing vertically and perpendicular to the door structure and extending sufficiently in front of the finished panel to provide a connection or pivot 23 upon which is mounted the side rails of a bed frame 25.

The traveler hinge plates 22 project through a narrow slot or aperture 24 formed between one side of the door panel 13 and a molding strip 26 running parallel therewith. There are molding strips 26 sub-

stantially concealing the chambers in front of the guide rails 19 on which rollers 20 travel.

For the purpose of counterbalancing the weight of the bed structure 24, which is pivoted at 23 upon the traveling hinge plates 22, each of the traveler journals 21, which may be tubular, is connected by a removable cotter-pin 27 to a chain or other flexible element 28 which extends upwardly in the guide journals in front of the rails 19 and passes over sheaves 29 mounted in the upper corners of the skeleton frame 9, the chains 30 running inwardly toward guide sheaves 31 and thence running downwardly in the chamber of the hollow door structure and connecting with a counter-balance weight 32, which is slidably guided between the members of the skeleton frame 9, there being suitable sectional weights 33 which may be adjusted upon the lower weight 32, these weights being exposed below the bottom edge of the panel 13 for ready adjustment or removal.

Referring to Fig. 1, the bed frame 25 is shown as adjusted in horizontal position in front of the door structure 12, in which position the vertically traveling hinge plates or hangers 22 are drawn to their lowermost position on the guide rails 19 without relative angular change of position as to the door structure, but with relation to which hinge plate or hanger the bed has moved through an angle of 90°, so that it stands perpendicular to the door structure 12, and as the bed frame is moved to a vertical position, tilting about the pivots 23 on the hinge plates 22, the bed frame turns through an arc of 90° with relation to the hinge plates 22, to the position shown in Fig. 5, when it stands parallel with the door structure; meanwhile the hinge plates 22 are traveling upwardly in their fixed angular relation with the door structure 12.

Means for constantly maintaining the hinge plates 22 in their fixed angular position with relation to the door 12 comprise the following: The bed frame 25 is provided at its side rails, intermediate their ends, with pivots 34, upon which are mounted the outer swinging ends of carrier arms 35, one for each side of the bed, these arms being provided with slotted ends 36, mounted upon fixed pivots 37, in the door frame 9; these pivots 37 preferably being located slightly below the plane that the bed frame will assume when adjusted horizontally. As before stated, the traveling hinge plates 22 are connected to the counterbalance weight 32, which have the function of aiding in the vertical adjustment of the bed frame 25, which when moving upwardly is partly supported on the arms 35, swinging about the fixed pivots 37, the bed frame moving upwardly with the bedding exposed.

outwardly. During the upward movement of the bed frame from the position in Fig. 1, the hinge plates 22 are automatically sustained so that the pivots 23 remain in substantially the same horizontal plane with the rollers 20, being connected to the arms 35, adjacent their pivots 34, by thrust links 38, which are pivoted at 39 upon the carrier arms 35 and pivoted at 40 in the lower portions of the hinge plates 22. In operation it will be seen that as the bed 25 is moved upwardly, its outer end will swing downwardly about the pivots 34 in the ends of the arms 35, while these will swing upwardly through an arc of approximately 90°, the angular movement of the arms 35 acting through the thrust links 38 to constantly maintain the hinge plates 22 in their definite angular relation to the door structure 12 during their vertical movement in the slots 26; the arms 35-38 acting when the bed is moved downwardly from the position in Fig. 5, to maintain the plates 22 in their relative angular position with the door.

The purpose and advantage of providing hinge plates 22, as in the present instance, is that with these I am enabled to utilize practically the full length of the bed frame 25 for supporting and carrying the bedding, said bed frame being substantially of equal length with the height of the door. When the bed frame 25 is in its horizontal position, the inner or that end adjacent the door 12 is supported upon fixed legs 41, which may be provided with rollers 42, and the outer end of the bed is supported upon automatically folding legs 43 which are provided with felt-covered rollers 44 of relatively large diameter and considerable width, the upper ends of the legs being pivoted at 45 upon a transverse bar 46 of the bed frame.

For accomplishing the leg folding and positioning of the rollers 44 beneath the bed frame 25 during its adjustment from one position to another, I connect the legs 43 by operating links 47 to the arms 35 by pivots 48 adjacent the pivots 34 on the bed frame.

In operation when the bed frame 25 is moved from the vertical position, Fig. 5, to a horizontal position, Fig. 1, the downward swinging movement of the carrier arms 35 pulls the legs 43 downwardly from the position shown in Fig. 5, so as to bring the rollers 44 into bearing upon the floor; whereupon a part of the weight of the bed frame is taken up by the rollers and removed from the carrier arms 35 and the counterweight 32.

It is for the purpose of protecting the carpet from wear by the rollers 44 that the latter are made of considerable diameter and width, and preferably covered with a soft material; and to compensate for the differences in level which the bed frame may assume when adjusted horizontally I have

provided the slotted end 36 of the carrier arms 35; the slots providing sufficient play to allow the operating links 47 to draw the automatic leg frame 43 to the desired position without binding.

A further feature of my invention is to provide head and foot frame members 25, with reinforcements as the truss rod 25, which so stiffen the end members as to prevent their flexure or bowing under the tension of the bed springs 50, the result of which would be to cramp or bind the operating mechanism of the bed structure.

A further important feature of my present invention is to provide a movable head frame 51, which is so connected to the bed frame 25 that it may be thrown downward and forward over the central portion of the bed frame, this connection comprising brace links 52 pivoted at their outer ends at 53 to the head frame 51 and at their fulcrum ends by pivots 54 to the bed frame 25, and also connected by radius links 55, which are pivoted at their fulcrum ends at 56, to the bed frame, and at their outer ends are connected by pivots 57 to the adjacent ends of the head frame 51. Preferably the fulcrum ends of the links 55 are slotted, as at 58, for the purpose of allowing the head frame 51 to adjust itself parallel with the bed frame 25 under varying thicknesses of bedding upon the springs 50. A movable foot frame 60 is also provided which is adapted to be drawn forward and over the bed so that its transverse end will come into juxtaposition and parallel with the transverse bar of the head frame 51; the foot frame 60 being connected by links 61, pivoted at their swinging ends at 62, to the foot frame, and at their fulcrum ends to pivots 63 on the bed frame. Other links 64 are slidably connected by pins 65 to the leg portions of the foot frames and pivoted at 66 to the extreme ends of the bed frame 25, the links 64 being slotted at 67 also for the purpose of allowing the foot frame 64 to maintain parallel positions with relation to the bed frame 25 under varying thicknesses of bedding on the springs 50.

The head frame 51 and the foot frame 60 have the function when thrown forwardly over the central portion of the springs 50, with their transverse bars in parallel juxtaposition, of firmly holding the bedding upon the springs when the bed is moved into vertical position, these frame members being latched together by a hasp 68 turnable about a pivot 69 on the foot frame 60, and which has apertures 70 engageable with a pin 71 on the head frame 51; the hasp with the several apertures providing for securely fastening the head frame and foot frame in binding position upon the bedding, which may vary in thickness as stated.

Having thus described my invention what

I claim and desire to secure by Letters Patent, is:

1. The combination in a wall bed structure, with a wall having a doorway, of a hollow door, a bed frame adjustable thereon, counterweights in said door, and means connecting said weights and the bed frame. 70
  2. The combination in a wall bed structure, with a wall having a doorway, of a hollow, revoluble door, a bed frame adjustable thereon, counterweights in said door, and means connecting said weights and the bed frame. 75
  3. A door structure for carrying a wall bed comprising a rectangular skeleton, front and rear spaced removable panels one of which is of substantially equal width of its doorway and the other of less width, and means for attaching the bed to the structure. 80
  4. A door structure for carrying a wall bed comprising a rectangular skeleton, front and rear spaced removable panels one of which is of substantially equal width of its doorway and the other of less width, means for attaching the bed to the structure, and molding strips extending parallel to the vertical edges of the smaller panel forming channels for the bed connections. 85
  5. A door structure for carrying a wall bed comprising a rectangular skeleton, front and rear spaced removable panels one of which is of substantially equal width of its doorway and the other of less width, means for attaching the bed to the structure, and a central vertical pivot member mounted in said skeleton for adjustment in head and floor bearings and about which the door may revolve. 90
  6. A door structure for carrying a wall bed comprising a rectangular skeleton, front and rear spaced removable panels one of which is of substantially equal width of its doorway and the other of less width, means for attaching the bed to the structure, and a central vertical pivot member mounted in said skeleton for adjustment in head and floor bearings and about which the door may revolve, said pivot being to one side of the center line of the thickness of the door so that the wide panel will engage opposite sides of a central stop on a jamb of the doorway. 95
  7. In combination with a wall having a doorway with jambs at its sides, one of which has a bead stop, a door structure mounted to revolve in the doorway from a position on one side of said bead to a parallel position on the other in which it is stopped by the bead, said door having a vertical shaft eccentric to the center of thickness of the door, vertical guides on one side of the door, travelers running in the guides, pivots in said guides, and a bed structure connected to said travelers and said latter pivots. 105
  8. In combination with a wall having a doorway with jambs at its sides one of which
- has a bead stop, a door structure mounted to revolve in the doorway from a position on one side of said bead to a parallel position on the other in which it is stopped by the bead, said door having a vertical shaft eccentric to the center of the thickness of the door, vertical guides in one side of the door, travelers running in the guides, pivots in said guides, a bed structure connected to said travelers and said latter pivots, and a counterbalance concealed in the door and attached to the travelers. 110
9. In a bed structure, a support with spaced guides on one side, travelers operating in the guides and projecting therefrom, a bed frame pivoted upon the travelers at one end, and carrier arms pivoted upon the said support and connected at their swinging ends to said bed. 115
10. In a bed structure, a support with spaced guides on one side, travelers with rollers operating in the guides and projecting therefrom, a bed frame pivoted upon the travelers at one end, and carrier arms pivoted upon the said support and connected at their swinging ends to said bed. 120
11. In a bed structure, a support with spaced guides on one side, travelers with rollers operating in the guides and projecting therefrom, a bed frame pivoted upon the travelers at one end, carrier arms pivoted upon the said support and connected at their swinging ends to said bed, and automatic means for maintaining the angular relation of the travelers to the door during relative movement of the bed. 125
12. The combination with a door, of a bed frame of substantially equal length as the door, and means comprising hanger plates projecting from one side of the door for moving the adjacent end of the bed to and from the top of the door and holding the elevated frame in close proximity to the door. 130
13. The combination with a door having vertical guides, of a bed frame of nearly equal length as the door, movable to and from vertical and horizontal positions, and travelers movable in said guides and having pivots in front of the plane of the door upon which the bed is hung and whereby the full length of the bed is rendered usable when down. 135
14. The combination in a wall bed, of a supporting structure with vertical guides, traveling plates running on said guides and having bearings in front of said structure, a bed pivoted at one end in said bearings, and carrying arms pivoted upon said structure and connected at their swinging ends to the bed intermediate its ends, said arms drawing the bed toward said structure when moving up, while the bed suspended upon the travelers acts to force the upright arms back toward said structure. 140

15. The combination in a wall bed, of a supporting structure with vertical guides, traveling plates running on said guides and having bearings in front of said structure, a 5 bed pivoted at one end in said bearings, carrying arms pivoted upon said structure and connected at their swinging ends to the bed intermediate its ends, said arms drawing the bed toward said structure when moving up, while the bed suspended upon the travelers acts to force the upright arms back toward said structure, and a counterbalance connected to said travelers.
16. In a bed structure, a support, a bed-frame, means connecting said support and the adjacent end of the bed for moving the same upwardly with bedding outward, carrier arms connected to said support and to the frame intermediate its ends, and legs 20 pivotally connected to the frame and movable by said arms from a forwardly folded inoperative position parallel to the bed frame and independent of the floor to a position perpendicular to the frame when the 25 latter is horizontal for supporting the outer end of the frame.
17. In a bed structure, a support, a bed-frame foldably related to said structure to move vertically at its head end, travelers 30 guided along the support and to which the bed frame is pivoted in front of said structure, counterweights for facilitating the movement of the bed, radius carrier arms connected to said structure and to the frame 35 and upon which the weight of the latter is imposed when vertical, and legs attached to the frame for supporting the foot end thereof when horizontal.
18. In a bed structure, a support, a bed-frame foldably related to said structure to move vertically at its head end, travelers 40 guided along the support and to which the bed frame is pivoted in front of said structure, counterweights for facilitating the movement of the bed, radius carrier arms connected to said structure and to the frame 45 and upon which the weight of the latter is imposed when vertical, and legs attached to the frame for supporting the foot end thereof when horizontal, said legs automatically 50 swinging toward the outer end of the frame during movement to vertical position.
19. In a bed structure, a support, a bed-frame foldably related to said structure to 55 move vertically at its head end, travelers guided along the support and to which the bed frame is pivoted in front of said structure, counterweights for facilitating the movement of the bed, radius carrier arms 60 connected to said structure and to the frame, and upon which the weight of the latter is imposed when vertical, and legs attached to the frame for supporting the foot end thereof when horizontal and being automatically 65 foldable against the foot end of the bed to clear the floor when the bed is vertical.
20. In a bed structure, a support, a bed, means connecting the bed to said support for moving its head in a vertical plane, radius arms pivoted to the frame at their outer ends 70 and having slots engaging pivots on said support, and folding legs pivoted to the frame for supporting the same in horizontal position, the slots in the arms allowing the legs to become perpendicular to the frame irrespective of varying thickness of floor covering.
21. In a bed structure, a support, a bed, means connecting the bed to said support for moving its head in a vertical plane, radius arms pivoted to the frame at their outer ends and having slots engaging pivots on said support, and folding legs pivoted to the frame for supporting the same in horizontal position, the slots in the arms allowing the legs to become perpendicular to the frame irrespective of varying thickness of floor covering.
22. The combination with a door having an eccentric pivot about which it is revolvable, of a bed-frame of substantially equal width as the door, and means comprising hangers on one side of the door for moving 95 the adjacent end of the bed to and from the top of the door.
23. The combination in a wall bed structure, with a wall having a doorway, of a hollow door, a vertical shaft extending 100 through and about which the door turns, and a bed-frame adjustable thereon.
24. In a folding bed, a support, a bed-frame, hangers movable along the support to which one end of the frame is connected for 105 controlling the same, carrier arms connected to the frame intermediate the ends, counter-balancing means connected to said hangers, and supporting means operated by said arms for taking a part of the load from the arms 110 and counter-balancing means when the frame assumes a horizontal position.
25. In a folding bed, a support, a bed-frame, hangers movable along the support to which one end of the frame is connected 115 for controlling the same, carrier arms connected to the frame intermediate the ends, counter-balancing means connected to said hangers, supporting means operated by said arms for taking a part of the load from the 120 arms and counter-balancing means when the frame assumes a horizontal position, and rests fixed to the support for bearing the adjacent end of the frame.
26. In a folding bed, a support, a bed 125 frame, hangers movable along the support to which one end of the frame is connected for controlling the same, carrier arms con-

nected to the frame intermediate the ends, counterbalancing means connected to said hangers, supporting means operated by said arms for taking a part of the load from the arms and counter-balancing means when the frame assumes a horizontal position, rests fixed to the support for bearing the adjacent end of the frame, and a foldable foot frame adjustable perpendicularly to the frame for relieving said supporting means of the load.

27. In a folding bed, a bed with head and foot frames which are adjustable parallel and perpendicular to the frame, and pairs of brace links and of radius links which connect the frames to the bed, said radius links having slotted ends engaging respective pins, whereby the frames will become parallel to the bed irrespective of variations, between predetermined limits, in thickness of bedding over which the frames are adjustable.

28. In a folding bed, a bed with head and foot frames which are adjustable parallel and perpendicular to the frame, pairs of brace links and of radius links which connect the frames to the bed, said radius links having slotted ends engaging respective pins, whereby the frames will become parallel to the bed irrespective of variations, between predetermined limits, in thickness of bedding over which the frames are adjustable, and a perforated hasp pivoted upon one of said frames and engageable with a complementary part on the other for locking the frames over bedding on the bed. 35

In testimony whereof I have hereunto set my hand in the presence of two subscribing witnesses.

PAUL BARNUM.
